Specification for Design.

Patented Dec. 10, 1918.

Application filed March 11, 1918. Serial No. 221,857. Term of patent 7 years.

To all whom it may concern:

Be it known that we, ARTHUR F. HEWITT and HARRY F. WATERS, citizens of the United States of America, residing at Denver, in the county of Denver and State of Colorado, have invented a new, original, and ornamental Design for a Vehicle-Body, of which the following is a specification, reference being had to the accompanying drawing, forming part thereof.

Figure 1 represents a plan view of a vehicle-body showing our new design, and Fig. 2, a side elevation of the same.

We claim:

The ornamental design for a vehicle-body, as shown.

ARTHUR F. HEWITT.
HARRY F. WATERS.
